UNITED STATES PATENT OFFICE.

ADIEL Y. DODGE, OF SOUTH BEND, INDIANA, ASSIGNOR TO BENDIX BRAKE COMPANY,
OF CHICAGO, ILLINOIS, A CORPORATION OF ILLINOIS.

BRAKE SHOE.

Application filed February 15, 1926. Serial No. 88,201.

This invention relates to brake shoes, and is illustrated as embodied in novel pressed-metal shoes for an internal expanding automobile brake.

5 An important object of the invention is to lessen the cost of a light but strong shoe of pressed metal, by forming it with a stiffening web including two portions integrally connected along their edges opposite the friction face of the shoe, thus permitting at least the major portion of the shoe to be all in one piece. Preferably these portions of the web are severed and spread apart, or otherwise formed, at one end of the shoe, to project as 15 spaced arms which appear in the drawings straddling the end of an adjacent shoe.

Other features of the invention relate to reinforcing the projecting integrally-connected arms by a separate part forming a 20 portion of the friction face of the shoe, to a novel wear plate engaging and reinforcing one end of the shoe, to the provision of openings for shoe-positioning means and for the anchor of an adjacent shoe, and to other novel 25 and desirable constructions which will be apparent from the following description of the illustrative embodiment shown in the accompanying drawing, in which:

Fig. 1 is a vertical section through the 30 brake, just inside the head of the drum, showing the shoes in side elevation;

Fig. 2 is an inside elevation of one end shoe;

Fig. 3 is a side elevation of the end shoe; 35 Fig. 4 is a section through any one of the shoes, on the line 4—4 of Fig. 1 or Fig. 3, showing the integral connection between the flanges forming the stiffening web;

Fig. 5 is a partial section on the line 5—5 40 of Fig. 3, showing the wear plate mounting; and

Fig. 6 is a section on the line 6—6 of Fig. 3, showing the spaced arms.

The brake illustrated includes a drum 10, 45 at the open side of which is a backing plate 12, and within which are arranged three shoes 14, 16, and 18, shoes 14 and 18 preferably being identical and interchangeable and shoe 16 being somewhat different in construction. Shoe 14 is pivoted on an anchor 20 passing through a relatively large opening in the stiffening web of shoe 16, while shoe 16 is pivoted on an anchor 22 passing through relatively large openings 24 in arms 26 at the

end of shoe 14. Anchors 20 and 22 may be 55 connected by a reinforcing plate 28.

The brake is applied by means such as a double cam 30, against the resistance of a return spring 32, and shoe 18 is connected to the unanchored end of shoe 16 by a pivot 34 so that shoe 18 forces shoe 16 against the drum against the resistance of an auxiliary spring 36. The free ends of shoes 14 and 18 carry novel cam-engaging wear plates 38, and are positioned laterally by a plate 40 60 engaging the edges of the wear plates and carried by posts 42 secured to backing plate 12 and projecting through openings 44 in shoes 14 and 18.

The general organization of this brake is 70 fully described and claimed in prior applications, the present application relating to the construction of the shoes. Part of the subject-matter herein claimed is to be regarded as continued from my prior application No. 75 754,711, filed December 8, 1924, issued on March 22, 1927, as Patent No. 1,622,133.

Each of the shoes is pressed or otherwise formed from sheet metal, in a manner providing oppositely-extending cylindrical 80 flanges 52 forming most of the friction face of the shoe, and which are preferably integral with integrally-connected portions or webs 54 which jointly form a double-thickness stiffening web for the shoe, and which 85 are arranged between the edges of the shoe. Portions 54 engage each other back to back, and may be riveted or spot-welded or otherwise secured together. Lining 56 of any desired character is secured to the friction face 90 flanges 52, for example by riveting.

At the upper end of each of the shoes 14 and 18, the ends of the stiffening-web portions 54 are straddled by spaced portions 58 of the wear plate 38, shown secured to the 95 stiffening web by rivets 60 in such a manner as to transmit brake-applying thrust to both portions of the web. Openings 44 extend part way into portions 58, forming notches in the edges of those portions (Figs. 3 100 and 5).

At the other end of each of the shoes 14 and 18, portions 54 are severed from each other at their inner edges, and spread apart, to form the arms 26 straddling the corresponding end of shoe 16. These arms, as will be apparent from Fig. 1, are curved sharply inward, or otherwise offset within

the curve of the friction face, so that they do not interfere with the friction face of shoe 16.

Preferably the friction faces of shoes 14 and 18 are extended by parts such as plates 64 bridging arms 26. Flanges 52, where they extend onto arms 26, are depressed so that plates 64 form parts of the friction faces of the shoe. Thus each of the shoes 14 or 18 is T-shaped in cross section throughout most of its length, but is of a channel section where arms 26 are bridged by plate 24, while arms 26 project a substantial distance beyond the friction face. Preferably tubular sleeves, or integral bushings, 66 are drawn on arms 26 to encircle anchor 20 or pivot 34.

Shoe 16, on the other hand, is preferably of T section throughout its length. At its right end, Fig. 1, double-thickness web 54 is offset within the curve of the friction face to clear plate 64 of shoe 14, and pivoted on anchor 22. At its left end, Fig. 1, portions 54 of shoe 16, which are elsewhere integrally connected along their inner edges as in Fig. 4, are severed and reduced in width (measuring inwardly from the friction face), to form a tapering part overhanging pivot 34 and the end of shoe 18. Arms 26 of shoe 18 are offset within the curve of the friction face to clear this overhanging part of shoe 16.

While particular shoes have been described in detail, it is not my intention to limit the scope of the invention to those particular shoes, or otherwise than by the terms of the appended claims.

I claim:

1. A brake shoe of sheet metal having between its edges a double-thickness stiffening web including two single thickness portions integrally connected at the edge opposite the friction face of the shoe.

2. A brake shoe of sheet metal having a cylindrical outer friction face and having between its edges a stiffening web extending inwardly and including two portions integrally connected at their inner edges.

3. A brake shoe of sheet metal having between its edges two integrally-connected stiffening web portions spread apart at one end of the shoe to form spaced arms.

4. A brake shoe of sheet metal having a cylindrical outer friction face and having between its edges a stiffening web extending inwardly and including two portions integrally connected at their inner edges, said portions being severed and spread apart at one end of the shoe to form spaced arms.

5. A brake shoe of sheet metal generally T-shaped in cross-section, with the friction face of the shoe consisting of oppositely-directed flanges each integral with a radial portion, and with the said portions integrally connected and jointly forming a stiffening web.

6. A brake shoe of sheet metal generally T-shaped in cross-section, with the friction face of the shoe consisting of oppositely-directed flanges each integral with a radial portion, and with the said portions integrally connected and jointly forming a stiffening web, and with the said portions severed and spread apart some distance from one end of the shoe. 70

7. A brake shoe of sheet metal including a pair of integrally-connected portions spaced apart and forming arms at least at one end of the shoe, in combination with a separate part bridging across the arms and forming a part of the friction face of the shoe. 80

8. A brake shoe of sheet metal including a pair of integrally-connected portions spaced apart and forming arms at least at one end of the shoe and having oppositely-projecting cylindrical flanges, in combination with a separate plate bridging across the arms and secured to and overlapping the cylindrical flanges and forming a part of the friction face of the shoe. 90

9. A brake shoe of sheet metal having between its edges a stiffening web including two portions integrally connected along the edge opposite the friction face of the shoe, the portions being severed from each other some distance from one end of the shoe and spread apart to form spaced arms, in combination with a separate part bridging across and reinforcing said arms and forming a part of the friction face of the shoe. 100

10. A brake shoe of sheet metal having between its edges a stiffening web including two integrally-connected portions spread apart from each other some distance from one end of the shoe to form spaced arms, in combination with a separate part bridging across and reinforcing said arms and forming a part of the friction face of the shoe. 105

11. A brake shoe of sheet metal having a stiffening web including two portions engaging each other back to back, in combination with a separate wear plate at one end of the shoe having a pair of backwardly-projecting spaced portions straddling the end of the stiffening web and transmitting 110 brake-applying thrust to both of said portions.

12. A brake shoe of sheet metal having between its edges a stiffening web including two portions integrally-connected along their edges opposite the friction face of the shoe and engaging each other back to back, in combination with a separate wear plate at one end of the shoe engaging the end of the stiffening web and transmitting brake-applying thrust to both of said portions. 120

13. A curved brake shoe of pressed metal having a pair of integrally-connected spaced arms projecting a substantial distance beyond the friction face at one end of the shoe, 130

- and offset within the curve of said friction face, to overlap the end of an adjacent shoe. 45
14. A curved brake shoe of pressed metal having a pair of integrally-connected spaced arms projecting a substantial distance beyond the friction face at one end of the shoe, and offset within the curve of said friction face, to overlap the end of an adjacent shoe, the arms being formed with opposite relatively large openings to afford clearance for the anchor of said adjacent shoe. 50
15. A brake shoe of pressed metal having two stiffening web portions integrally connected along the edge opposite the friction face. 55
16. A brake shoe of pressed metal having two integrally-connected stiffening web portions, and having a pair of spaced arms at one end of the shoe. 60
- 20 17. A brake shoe of pressed metal having two integrally-connected stiffening web portions, and having a pair of spaced arms at one end of the shoe and having an opening through the stiffening web portions near the other end of the shoe. 65
- 25 18. A brake shoe of pressed metal having two integrally-connected stiffening web portions, in combination with a wear plate engaging said portions at one end of the shoe, said portions having a relatively large opening adjacent the wear plate. 70
- 30 19. A brake shoe having a stiffening web between its edges, in combination with a wear plate having spaced portions straddling one end of the web, and formed with an opening through the web extending at least in part through said portions of the wear plate. 75
- 35 20. A brake shoe of pressed metal having between its edges a stiffening web including two portions integrally connected along their edges opposite the friction face of the shoe and secured to each other back to back, the stiffening web portions being severed and re- 80
- duced in width measured inwardly from the friction face, near one end of the shoe, to form a tapered portion overhanging an adjacent shoe. 85
21. A brake shoe of pressed metal having between its edges a stiffening web including two portions integrally connected along their edges opposite the friction face of the shoe and secured to each other back to back, the stiffening web portions being severed and reduced in width measured inwardly from the friction face, near one end of the shoe, to form a tapered portion overhanging an adjacent shoe, the stiffening web projecting beyond the friction face at the other end of the shoe and offset within the curve of the friction face, to form an anchoring arm. 90
22. A brake shoe the main body portion of which is formed from a single sheet of metal to present a single thickness brake lining attaching surface and a double thickness web. 95
23. A brake shoe the main portion of which is formed from a single sheet of metal to present a single thickness brake lining attaching surface and a double thickness web, said web being formed by bending said metal back on itself. 100
24. A brake shoe the main body portion of which is formed from a single sheet of metal into a T-shaped section formed by bending such sheet to simulate two L-shaped portions secured back-to-back at their inner ends. 105
25. A brake shoe formed from a single sheet of metal, the main body portion of which comprises a reversely bent web connected at the free edge thereof and oppositely extending edge portions disposed perpendicularly thereto. 110
- In testimony whereof, I have hereunto signed my name. 115
